US00D545964S

(12) **United States Design Patent** (10) Patent No.: **US D545,964 S**
(45) Date of Patent: ** Jul. 3, 2007

(54) **COMBINED SEAL AND VALVE ASSEMBLY**

(75) Inventor: **Ernesto E. Blanco**, Belmont, MA (US)

(73) Assignee: **Erblan Surgical, Inc.**, Belmont, MA (US)

(**) Term: **14 Years**

(21) Appl. No.: **29/208,947**

(22) Filed: **Jul. 9, 2004**

(51) LOC (8) Cl. 24-01

(52) U.S. Cl. D24/129

(57) **CLAIM**

The ornamental design for a combined seal and valve assembly, as shown and described.

DESCRIPTION

FIG. 1 is a top, front and left side perspective view of the valve of the seal valve assembly, showing my design;

FIG. 2 is a left side elevational view thereof, the right side elevational view being a mirror image of the side view shown;

FIG. 3 is a top plan view thereof, the bottom plan view being a mirror image of the plan view shown;

FIG. 4 is a bottom plan view thereof;

FIG. 5 is a front elevational view thereof;

FIG. 6 is a rear elevational view thereof;

FIG. 7 is a top, front and left side perspective view of the seal of the seal valve assembly;

FIG. 8 is a left side elevational view thereof, the right side elevational view being a mirror image of the side view shown;

FIG. 9 is a front elevational view thereof;

FIG. 10 is a rear elevational view thereof;

FIG. 11 is a top plan view thereof, the bottom plan view being a mirror image of the plan view shown;

FIG. 12 is a top front and left side perspective view of the seal valve assembly for use with a trocar;

FIG. 13 is a left side elevational view thereof, the right side elevational view being a mirror image of the side view shown;

FIG. 14 is a front elevational view thereof;

FIG. 15 is a rear elevational view thereof;

FIG. 16 is a top plan view thereof, the bottom plan view being a mirror image of the plan view shown;

FIG. 17 is a bottom plan view thereof; and,

FIG. 18 shows the seal, the valve and the seal valve assembly when in use in a trocar.

The broken lines shown throughout the drawing disclosure are for illustrative purposes only and form no part of the claimed design.
